GATE VALVE FOR RUNWAYS

Filed Nov. 16, 1931

UNITED STATES PATENT OFFICE

DAVID LEO CRAMP, OF KIRKLAND LAKE, ONTARIO, CANADA

GATE VALVE FOR RUNWAYS

Application filed November 16, 1931. Serial No. 575,303.

The invention relates to a gate valve for runways, as described in the present specification and illustrated in the accompanying drawing which forms part of the same.

The invention consists essentially of the novel means employed in retarding the progress of ore or waste material traveling down the chutes and also means for allowing the ore or waste material to gradually pass through as pointed out in the claims for novelty following an explanation in detail of an acceptable form of the invention.

The objects of the invention are to speed up loading operations in mines and other places; to devise a means whereby the ore or other material will be regulated in its discharge from the runway and thereby eliminate the danger of accidents to the workmen and others as well as avoid possible dangers to the chute structure and the loading cars; to simplify the chute controls for handling the material; and generally to provide a gate valve for runways which will be comparatively cheap to manufacture, durable in construction, and efficient for the purpose set forth.

In the drawing, Figure 1 is a side sectional view of the chute and gate valve.

Figure 2 is a vertical sectional view taken on the lines 2-2 of Figure 1.

Figure 3 is an enlarged detail of one of the gate weights.

Figure 4 is an enlarged perspective view of the lift bar.

Figure 5 is a side sectional view of a modified form of the invention as applicable in mines.

Like numerals of reference indicate corresponding parts in the various figures.

Referring to the drawing, the gate valve indicated by the numeral 10 is formed of the chains 11 strung from the shackles 12 rigid with the cross bar 13 and sufficiently near to one another to form obstructions to the passage of ore down the runway 14. These chains are secured by loops 15 to the weights or balls 16 which trail on the inclined flooring of the runway 14.

The chains continue in the links 17 from the loops 18 of the weights 16 and are at-

tached by shackles 19 to the lift bar 20 which is supported from a structural beam 21 by means of a cable 22 trained over the pulley 23 journalled in the bracket 24 which is secured to the structural beam 21. The cable 22 is secured at its lower end in the ring 26 which engages the looped ends 27 and 28 of the arms 29 and 30 pivotally mounted to the lift bar 20, although it is understood that cables could be utilized in place of the arms 29 and 30.

In the operation of the gate valve in its application to the chutes of various descriptions, such as chutes in mines or in car-loaders, etc., the waste ore or other substance slides down the runway until it engages with the gate valve which of course is lowered to its closed position. The material will consequently come into engagement with the chains of the gate which will act as a resistance thereto while the weights will form a barrier in preventing the material from sliding through.

When it is desired to discharge the material the lift bar of the gate is raised which immediately raises the weights from engagement with the runway and thereby enables the material to slip therebeneath and the speed or quantity of material that is required is controlled by merely lifting or lowering the lift bar which lifts up the weights and also the chain lengths and naturally the higher the lift bar is raised, the greater quantity of ore or other material will be discharged.

When it is desired to stop the discharge of ore or other material, the lift bar is simply lowered and it will immediately engage with the onrushing material, entangling the same among the chain lengths and immediately stop the flow.

In this way it will be seen that the common danger of a sudden rush of material down the chute will be eliminated and thereby avoid severe injuries to workmen and others which so often occurs in loading operations.

The size of the chains and chain weights is of course guided by the work in which it is to be applied such as if it is to be used for loading cars, the chains and weights may be

smaller or greater as desired and the same is reference to mines or in loading ships.

It is of course understood that the gate valve may be altered to meet with the various requirements, such as, if it is used for grain, a shield or other wall structure may be added to the lift bar but the chain lengths will remain.

What I claim is:

10. 1. A gate valve for runways comprising vertically hung parallel chains weighted and trailing on a runway and means for lifting the trailing weights.
15. 2. A gate valve for runways comprising hanging chains adjacent to one another and looped to ball weights in a runway and cables linked to said weights and trained over a pulley suitably supported.
20. 3. In a gate valve for runways, weights engaging with the inclined flooring of said runway, flexible means connected to said weights and rearwardly supported to the upper portion of the runway and flexible means secured to a lifting means adjacent to the discharge outlet of the runway and connected to said weights, and means for operating said lifting means.
25. 4. In a gate valve for runways, a flexible gate secured at one end to the runway structure and pivotally mounted and operated at the other end of the runway structure and having intervening weights adapted to abut the inclined flooring of said runway.
30. 5. In a gate valve for runways, a flexible gate supported by a cross bar at one end of the runway and at the other end to a lift bar supported and operated from a cross beam of the runway, and weights abutting the inclined flooring of said runway and secured to said flexible gate between said lift bar and cross bar.
35. 6. In a gate valve for runways, a rear support and a forward support secured to the discharge ends of the runways, chain lengths extending downwardly from said rear support and said forward support, and chain weights connecting the rear and forward chain lengths together and abutting the inclined flooring of the runways.
40. 7. In a gate valve for runways, a rear support and a forward support secured to the discharge ends of the runways, a plurality of chain lengths projecting downwardly from said rear support, a lift bar supported from said forward support and having chain lengths projecting therefrom and weights connecting the rear and forward chain lengths together and engaging with the sloping flooring of the runway and means for lifting and lowering said lift bar.
45. 8. In a gate valve for runways, hanging chains suitably supported in said runway and secured by loops at their lower ends to chain balls, a plurality of hanging chains supported from a lift bar and secured by

loops at their lower ends to chain balls, and means for lifting and lowering said lifting bar.

9. In a gate valve for runways, a rear support and a forward support secured to said runways, a plurality of hanging chains secured to said rear support, a plurality of weights having loops secured to the lower ends of said hanging chains and abutting the sloping flooring of said runway, a lift bar having a yoke and a cable connected thereto and supported from said forward support and suitably operated, a plurality of hanging chains secured to said lift bar and of shorter length than of said rear hanging chains and connected by loops to said weights.

10. In a gate valve for runways, forward and rear supports, hanging chains secured to said forward and rear supports, and weights intervening in each of said hanging chains and forming a chain angle in relation to the forward and rear supports, and means mounted on said forward support for lifting or lowering said hanging chains.

Signed at Kirkland Lake, Canada, this 24th day of September, 1931.
